UNITED STATES PATENT OFFICE.

GEORGE GOODLINE, OF PHILADELPHIA, PENNSYLVANIA, ASSIGNOR
TO CROMPTON-THAYER LOOM COMPANY, OF WORCESTER, MASSA-
CHUSETTS.

STOP-MOTION FOR LOOMS.

SPECIFICATION forming part of Letters Patent No. 777,089, dated December 13, 1904.

Application filed January 15, 1904. Serial No. 189,087. (No model.)

To all whom it may concern:

Be it known that I, GEORGE GOODLINE, a citizen of the United States, residing at Philadelphia, county of Philadelphia, State of Pennsylvania, have invented an Improvement in Stop-Motions for Looms, of which the following description, in connection with the accompanying drawings, is a specification, like characters on the drawings representing like parts.

This invention has for its object to improve and simplify the construction of stop-motion means employed in looms, especially stop-motion means made operative on the failure of the shuttle to be properly boxed, as it will be understood that if the loom is not instantly stopped the portion of the shuttle projecting outwardly from the box will as the lay is moved forward "smash out" the warps. I have also shown provision for releasing the shipper-lever whenever for any reason the weft fails to be laid in a shed; but such feature is not herein claimed.

As I have herein chosen to illustrate my invention the crank-shaft has applied to it a friction-clutch, one member of which is represented as a loose pulley and the other as a disk; but I may employ any usual friction-surfaces. I have provided means between the shipper-handle and the lever controlling the position of the loose friction-pulley with relation to the fast friction-disk whereby the degree of pressure of said friction-faces when in use may be determined accurately and made more or less. I have also improved the construction of the brake that coacts with the brake-pulley on the crank or other shaft when the loom is to be stopped and have provided means whereby the brake may be readily thrown off by hand whenever the operator desires to turn the loom over by hand.

Figure 1 in perspective shows a sufficient portion of one end of a loom with my improvements added to enable my invention to be understood. Fig. 2 is an end view of the parts of the loom shown in Fig. 1. Fig. 3 is a detail showing some of the parts of Fig. 2, but in a different position. Fig. 4 is a section taken inside the loom-frame to show the dagger, the binder, and binder-finger; and Fig. 4^a

shows the part of the loom-frame with the square hole therein containing the square part of the bolt a^6 . Fig. 5 is a view showing the parts of the loom below the breast-beam and the race of the lay.

A represents the end frame of the loom, A' the crank-shaft; A², Fig. 4, part of the usual connecting-rod intermediate said crank-shaft and the lay A³, which latter is pivoted in usual manner. (Not herein shown.) The crank-shaft has fastened to it a toothed gear A⁵, that engages a larger gear A⁶ on and rotates the cam-shaft A⁷. The crank-shaft has fast upon it at one side of the gear A⁵ a brake-pulley A⁸ and at its opposite side the fast member B of a friction or clutch pulley, the other member, B', being loose on the crank-shaft, said members having smooth faces, which are forced in contact, as will be described, when the crank-shaft A' is to be rotated.

A hub B² of the loose member B' of the friction-clutch abuts a collar B³, slidably mounted on the crank-shaft A', so that when said collar is moved to the left, Fig. 1, the loose member B' will be made to engage the fast member B and rotate the crank-shaft, thus driving the loom. The loose member has an opening leading into an oil-chamber forming part of said member, such construction being common and not herein claimed.

The collar B³ has extended from it one or more studs B⁴, that are embraced by a strap-like portion of a lever B⁵, mounted to turn about a stud B⁶, sustained by an upright B', erected from the floor at a short distance from the loom end.

The lever B⁵ has a stud a, that receives an eye at one end of a two-part adjustable connection, shown as a rod a', threaded, and thereby made adjustable in a screw-threaded rod-head a², that is connected by a stud a³ with one arm a⁴ of a rock-shaft a⁵, having suitable bearings a⁶ to sustain journals at the ends of said rock-shaft, said rock-shaft having connected with it at one end the shipper-lever a⁷, which is made of spring-steel and so bent that the front side of the rod acts with a considerable friction against the edge 2 of the slot 3 in the shipper-guide plate 4, in

which said shipper is movable. This shipper, owing to its springy quality, acts always in all positions of the shipper against a lever b , pivoted at b' and provided with a right-angled portion $b^2 b^3$, the portion b^2 standing always in and partially filling the shipper-holding notch 5, while the longer part b^3 of the right-angled portion is extended downwardly below the shipper-guide plate and has a shoulder 6. (See Fig. 1.)

A short arm b^4 , extended from the rock-shaft a^5 , to which is secured the shipper-lever, has connected with it a strong spiral spring b^5 , attached at its upper end to a screw-rod b^6 , extended through a guideway b^7 and provided with a nut b^8 , the adjustment of which on the screw-rod changes the effective tension of the spring b^5 , so that said spring will act with greater or less celerity in moving the shipper-lever from the shipper-holding notch 5 into its outward position, Fig. 1, which is of advantage in many ways in a quick-operating loom.

That the friction between the loose and stationary clutch members of the clutch may be controlled exactly according to the requirements of the work and to provide for wear an eye at one end of the rod a' may be slipped off the stud a after withdrawing the cotter-pin 10, and the rod may be turned in one or the other direction and be then reapplied to the stud and the cotter-pin inserted.

Fig. 1 shows a weft-fork-carrying slide c , supposed to be mounted in usual guides on the breast-beam and constructed when the filling is absent to be moved outwardly in any usual manner to thereby turn the lever c' , pivoted at c^2 , and cause said lever to act against the portion b^2 of the right-angled extension 40 of the lever b and throw the shipper-lever out of its notch, thus releasing the friction immediately.

To stop the loom when the shuttle fails to be boxed, the lay is provided at its under side 45 with a dagger-shaft f , having a dagger f' , and said shaft has a projection upon which is mounted the usual binder-finger f^2 , that bears on the shuttle-box binder f^3 . The finger is kept normally in contact with the binder by 50 a spring of usual construction surrounding the shaft f' , (not shown,) so that whenever the shuttle fully enters the box the shuttle moves the binder outwardly and acting through the binder-finger puts the dagger in 55 its inoperative or dotted-line position, Fig. 4. Should, however, the shuttle fail to fully enter its box, then the binder will not be moved outwardly, and the dagger will stand in its full-line position, Fig. 4. The dagger when in 60 its full-line position, Fig. 4, will strike and move a slide f^4 longitudinally on usual suspending means and will cause a projection f^5 of said slide to act upon one end of a short lever f^6 , mounted on a stud f^7 , and will turn the short 65 arm of said lever then in contact with the usual

lever f^8 , pivoted at f^9 on the under side of the breast-beam, and will move the latter lever in the direction of the arrow, Fig. 5, causing its outer end in contact with the right-angled portion of the arm b to move said arm in a direction to disengage the shipper from its usual holding-notch, which will not only release the friction-clutch members to stop the loom, but will also release the lever d' , that the brake may be put upon the brake-pulley. 75 This movement of the lever b disengages the notch 6 of the right-angled portion b^3 from the projection d , extended from the auxiliary lever d' , mounted to turn on a stud D^2 , permitting through rod d^4 the expanded spring d^5 , surrounding the bolt d^6 , to move from the position Fig. 2 into the position Fig. 3, causing the brake to meet the brake-pulley A^4 and immediately stop the loom.

To enable the effective strength of the 85 spring d^5 to be increased, the bolt d^6 has a head d^{12} , and said bolt just below its head is of other shape than round, preferably square, as shown in Fig. 4^a, and fits a square hole d^{13} in a portion of the loom-frame. The threaded 90 lower end of the bolt below the spring has attached to it a spring-rest e and an adjusting-nut e' , and to increase the tension of the spring it is only necessary to turn the nut on the non-rotative bolt. If the bolt was capable of being rotated in a round hole in the loom-frame instead of a hole other than round, as herein illustrated, it would be necessary to also hold the bolt when the nut was to be rotated. As the lever d' is moved from the position Fig. 2 into the position Fig. 3 it raises, through the plate 4, a manually-controlled rod D , and the loom having been stopped and the operator desiring to turn the crank-shaft by hand must first remove the brake 105 from the brake-wheel, and to do this it is necessary only to depress the manually-controlled rod D and move the auxiliary lever d' from the position Fig. 3 into the position 110 Figs. 1 and 2. As the lever d' is moved by the rod D the projection d is moved downwardly in contact with the right-angled portion of the arm b until the stud comes opposite the notch therein, when said arm then under the influence of the springing shipper-lever will engage said projection and hold the brake-lever in its inoperative position, as raising the rod d^4 turns the lever d^8 , so that the shoe d^7 will be removed from contact with the brake-pulley. In this condition the crank-shaft may be turned by hand in usual manner. To start the loom running properly, one has only to move the shipper-lever to engage its holding notch. 115

Having described my invention, what I 125 claim, and desire to secure by Letters Patent, is—

1. In a loom, a shaft having a brake-pulley, a pivoted brake-lever, a non-rotative bolt threaded at its lower end and extended loosely 130

through the end of said lever behind said 5
brake-pulley, a nut on said threaded bolt, and
a spring interposed between said nut and the
under side of said brake-lever whereby by
turning said nut on said non-rotative bolt the
pressure of the spring for actuating the brake- 10
lever and forcing it against the brake-pulley
may be regulated as desired, combined with a
manually - controlled rod, a lever actuated
thereby, and a link uniting one end of said
lever with the front end of said brake-lever.
2. In a loom, a shaft having a brake-pulley,
a pivoted brake-lever, a non-rotative bolt
threaded at its lower end and extended loosely
15 through the end of said lever behind said
brake-pulley, a nut on said threaded bolt, and
a spring interposed between said nut and the
under side of said brake-lever whereby by
turning said nut on said non-rotative bolt the
20 pressure of the spring for actuating the brake-
lever and forcing it against the brake-pulley
may be regulated as desired, combined with a
manually - controlled rod, a lever actuated
thereby, and a link uniting one end of said
25 lever with the front end of said brake-lever,
and means for locking automatically the lever
actuated by said manually-controlled rod to
hold the brake-lever out of contact with the
brake-pulley.
3. In a loom, a binder, a shaft having a
brake-pulley, a dagger controlled as to its po- 30
sition by the binder, a pivoted brake-lever, a
brake-spring to force the brake-lever against
the brake-pulley, an auxiliary lever located at
35 the loom side, an adjustable connection be-

tween said auxiliary lever and said brake-lever,
means to lock the auxiliary lever in position
to retain the brake-spring compressed,
and devices intermediate said dagger and the
locking means for said auxiliary lever to move 40
said locking means and release said auxiliary
lever when the brake is to be applied.

4. In a loom, a shaft having a brake-pulley,
a dagger controlled by the position of the
binder, friction members coacting with said 45
shaft, a shipper-lever, a notched plate for
holding said shipper-lever in operative posi-
tion, means moved by said dagger when the
shuttle fails to be properly boxed to release
the shipper-lever from its notch, a spring to 50
move said lever outwardly when released,
means controlled by said shipper-lever when
moved outwardly to quickly disengage said
friction members preparatory to stopping
the loom, a pivoted brake-lever, a spring nor- 55
mally held compressed by said brake-lever
when the loom is running, means to lock the
brake-lever in its inoperative position, the re-
leasing of the shipper-lever disengaging the
means for locking the brake-lever in its op- 60
erative position, and permitting its actuating-
spring to expand and force the brake-lever
against the brake-pulley.

In testimony whereof I have signed my name
to this specification in the presence of two sub- 65
scribing witnesses.

GEORGE GOODLINE.
